COIN-FREED APPARATUS

Walter A. Travers and Hugh Ernest James Butler, London, England; said Travers assignor to Automatic Telephone & Electric Company Limited, Liverpool, England, a British company, and said Butler assignor to Hall Telephone Accessories Limited, London, England, a British company

Application October 30, 1950, Serial No. 192,928

Claims priority, application Great Britain
November 5, 1949

2 Claims. (Cl. 179—6.3)

1

The present invention relates to coin-freed apparatus and is more particularly concerned with coin-freed apparatus for permitting the completion of an electrical circuit, for instance for controlling the reception of radio or other entertainment programmes in hotel bedrooms.

Time switch-controlled devices of this type are known which in response to the insertion of a coin enable a radio programme to be received during a predetermined period. These are however relatively expensive and it is the chief object of the invention to provide a device giving similarly effective facilities which is both inexpensive and simple to maintain and operate.

According to the invention a control unit for controlling the supply of audio frequency currents to a loudspeaker in response to the insertion of a coin or the like is arranged so that the presence of the coin serves to permit the effective movement of the external operating member of a switching member which is thereupon locked in operated position until released by the operation of a release member.

The invention will be better understood from the following description of one method of carrying it into effect which is given by way of example and should be taken in conjunction with the accompanying drawings comprising Figs. 1-4. Of these, Fig. 1 is a front elevation of the control unit. Fig. 2 is a side elevation. Fig. 3 is a section along the line Y—Y in Fig. 2 showing the mechanism mounted on the front cover, and Fig. 4 is a circuit diagram showing the electrical connections.

It is assumed that the control unit is used in association with loudspeakers in hotel bedrooms and is adapted in response to the insertion of a suitable coin, for instance a sixpence, to enable any one of a number of distributed radio or other programmes to be obtained as and when required. Each control unit is assumed to be suitably mounted on the wall or other vertical surface and the front face carries the volume control knob 13, the programme selection knob 14 and a knob 22 which in response to the insertion of a sixpence in the slot 21 may be moved to the right in the slot 23 in order to render the service operative. In the normal position of the device the knob 22 is locked so that it can perform only a limited movement and the loudspeaker is inoperative. The effect of inserting a sixpence is to free the control knob 22 which may then be slid to the right where it is retained in position and has the effect of altering the electrical connections so that the various radio programmes

2

are available under control of the knob 14. The control knob 22 may be subsequently tripped by the chambermaid or other hotel servant in a manner which will be described subsequently and it is then restored to its initial position by a spring and the radio programme is cut off and is only again available in response to the insertion of another coin.

Considering now more particularly Fig. 3, the main casing 10 of the control unit is provided with a cover 11 which is secured thereto by means of upwardly extending lugs on the brackets 15 and 16 secured to the cover which engage in corresponding slots on the casing. The cover is provided with an opening for a coin drawer 12 which is fitted with a suitable lock and is guided on the channel member 17 secured to the casing. The member 17 is also provided with an upstanding lug 18 provided with a threaded hole to take a screw 19 (visible in Fig. 1 where the front of the drawer is shown broken away). It will be seen therefore that to dismantle the equipment it is necessary first to unlock and remove the drawer 12 whereupon access can be obtained to the screw 19. When this is removed the lower portion of the cover may be swung forward and upward so that the lugs on brackets 15 and 16 disengage their corresponding slots and the cover may therefore be removed.

The main moving portion of the mechanism is a slide member 24 to which the operating knob 22 is secured by the nut 25. The right-hand end of the sliding member 24 in Fig. 3 is provided with a cut-out portion 26 which co-operates with a pillar 27 to ensure that the slide performs a rectilinear motion as determined also by knob 22 and slot 23. The slide is normally urged to the right in Fig. 3 by a helical spring 28 which is anchored to the bracket 16 and at the other end is secured to a post 29 on the slide. This post also carries an insulating bush, which is not shown in the drawing, for operating the contacted springs MC when the slide is moved to the left. A member 30 attached to the slide forms a coin recess and is provided with a top member 31 and walls 32 defining the recess. A flat member 33 mounted close to the slide member 24 and pivoted at 34 serves to trap an inserted coin and this member is urged upwards by the spring 35 mounted on the knob 22, the upward movement of the member 33 being limited by the member 30. The member 24 also carries at its extremity a bell-crank lever 36 which is pivoted on the pin 37 and is normally urged in an anti-clockwise direction 55 against the lug 38 by the limb 39 of the spring

35. The slide 24 is also provided with a locking member 40 having a tooth 41 arranged to co-operate with the locking lever 42 which is pivoted about the point 43. This locking lever is urged in an anticlockwise direction by the helical spring 40 one end of which is hooked round the lever while the other bears against the post 27. The movement of the locking lever is limited by the stop member 45 secured to the cover. The insulating bush 59 seen in Fig. 2 indicates the entry for the loudspeaker and programme supply leads.

Considering now the operation of the device, in the normal or inoperative position, the various parts occupy the positions shown and under these conditions only limited movement of the slide member 24 by means of the knob 22 is possible since the tooth 41 shortly engages the up-standing edge 58 of the tooth 49 on the locking member 42. When however a suitable coin is inserted it depresses the member 33 so as to trap the coin and the lower edge of the coin engages with the inclined face 46 of the locking member. If the knob 22 is now moved to the right as seen in Fig. 1, the coin also will be moved to the left as seen in Fig. 3 and its lower edge engaging with the inclined face 46 of the locking member will cause this member to be rotated anticlockwise about the pivot 43 so that the tooth 49 is moved out of the path of the tooth 41. As the movement of the member 24 proceeds, tooth 41 passes to the other side of the tooth 49 and the coin engages the edge 47 of the locking member and subsequently passes clear of the vertical portion 48. It is then no longer supported and falls into the drawer 12 while the locking member, being no longer pressed downwards, returns to its original position as limited by the stop 45 so that the tooth 41 then engages with the vertical face 51 of the tooth 49 and the slide member 24 is prevented from returning to normal under the action of spring 28. The insulating bush carried by pin 29 will now have engaged the long middle spring of the springset MC and thus changed over the connections as will be appreciated from Fig. 4.

In this figure it is assumed that three different programmes are available over the pairs of conductors P1, P2 and P3 which are connected respectively to positions 1, 2 and 3 of the programme switch PS provided with wipers PS1 and PS2. The control unit is also intended to house a matching transformer TR which is not shown in Fig. 3 and this extends to the volume control rheostat VC and so to the loudspeaker by way of the bracketed leads LS. It will be seen that in the normal position the contacts MC short-circuit the primary winding of the transformer and that a similar state of affairs exists after operation of contacts MC as long as the programme switch PS is in the off position. As this switch is rotated to connect up an appropriate programme, the supply leads P1, P2 or P3 are connected through to the primary of the transformer TR so that the loudspeaker is energised accordingly as determined by the setting of the volume control rheostat VC. The user may of course switch off the programme by turning the switch PS to the "off" position and may obtain programme service subsequently without inserting any further coin provided the period covered by the original coin insertion has not yet expired. The length of this period is clearly at the discretion of the hotel management but for the service visualised it will generally be convenient to re-

store the control devices each day. The collection of the inserted coins can be effected at some considerably longer interval as is found desirable.

5 It will be appreciated that the position of the knob 22 forms a visible indication of whether the device has been used so that the hotel house-keeper or chambermaid can readily see whether any restoring operation is needed. Preferably this would normally be done round about breakfast time each morning when servicing of the bedrooms would be necessary in any event. Restoration of the device to normal is effected by means of the fingerplate 52 which covers a hole 53 in the wall of the casing 10. The finger plate is located by two studs passing through holes therein, the lower one 54 carrying a nut 55 which serves to retain a bowed spring 56 by means of which the fingerplate is normally urged into contact with the casing so as to close the hole 53. The upper stud carries a buffer 57 limiting the movement of the fingerplate when it is depressed against the action of the spring 56. If this is done while the control unit is in operated position, the turned-over end of the fingerplate 52 engages the vertical arm of the bell crank lever 36 and causes the horizontal arm to engage with the edge 58 of the locking member 42 and move it downwards. Thereupon the tooth 49 is moved out of engagement with the tooth 41 on the slide member 24 and this member is moved back to normal position by the action of spring 28. The springs MC are then restored to normal and effective movement of the slide member is again prevented until another coin has been inserted.

40 Alternatively a key-operated releasing device could be provided but this involves additional complication and if the releasing arrangement is concealed and not obviously accessible there is little likelihood of the user operating it inadvertently and if he does so by tampering with the unit he has only himself to blame if he loses his programme prematurely. A further alternative which might be justified in some circumstances would be to have the switches tripped electrically by an unlocking impulse sent over the whole programme distribution network from a central control position, for instance the main distribution point. The device thereupon remains in the inoperative position until it is again rendered operative by the insertion of a further coin.

50 Periodically the cashier or similar hotel official will visit the various bedrooms to collect the coins stored in the coin receptacles.

55 The invention therefore provides a satisfactory way of giving a facility which is often desired without involving the hotel management in comparatively heavy expense for installation, maintenance or operation.

60 We claim:

1. Switching apparatus of the coin freed type adapted to complete selected circuits of a programme distribution device comprising in combination, a casing having at least a pair of openings therein, a slide disposed internally of the casing and guided for reciprocating motion relative thereto, an operating link secured to the slide and extended through one of the openings in the casing to terminate in a control element, resilient means for maintaining the slide in a normally inoperative position, a set of electrical contacts in the circuits of the programme distribution system disposed internally of the casing, means effective to complete the circuits through

the contacts when the slide is moved to its operative position, locking means for securing the slide against movement from its inoperative position and from its operative position, means responsive to the insertion of a suitable coin to render the locking means ineffective to manual movement of the slide to the operative position through the medium of the control element, release means accessible through the other opening in the casing to render the locking means ineffective to return movement of the slide to the inoperative position under the influence of the resilient means, sound translating means, a matching transformer means for supplying the sound translating means with audio-frequency voltage, connections extending from the circuits of the programme distribution system via said contacts to the audio-frequency supplying means whereby audio-frequency voltages may be applied to the sound translating means during the interval when the slide is disposed in its operative position, said last named means including a switch normally connected to short circuit the transformer and to relieve the short circuit upon movement of the slide to its operative position.

2. Apparatus for actuating a switch in a programme distribution system in response to the insertion of a suitable coin comprising a frame, a slide guided for bilateral rectilinear motion relative to the frame, said slide having an operative and an inoperative position, an operating link secured to the slide for manual movement of the slide from the inoperative to the operative position, resilient means normally maintaining the slide in the inoperative position, a locking lever pivotally fastened to the frame in a position adjacent the slide, further resilient means biasing the locking lever in the direction of the slide, a tooth and a camming surface

disposed on the locking lever, a further tooth disposed on the slide in a position for abutting engagement with the locking lever tooth thereby to prevent movement of the slide to the operative position, coin receiving and trapping means disposed in proximity with the camming surface of the locking lever whereby a suitable coin is adapted to be held in contact with said camming surface and moved by the slide through manual operation of the operating link to partially revolve the locking lever and release the slide for movement to the operative position during which movement the coin is disengaged from the camming surface to permit the locking lever to return through the action of said further resilient means with the tooth thereof engaging the tooth of said slide to lock the latter in the operative position, a set of electrical contacts for the switch, means effective with the slide in the operative position to close the contacts, and means for releasing the slide to permit it to return to the inoperative position under the influence of said first mentioned resilient means.
